(57) **CLAIM**

The ornamental design for a base for a semiconductor carrier, as shown and described.

DESCRIPTION

FIG. 1 is a front view of a base for a semiconductor carrier showing our new design, the rear view being a mirror image thereof;

FIG. 2 is a top view thereof;

FIG. 3 is a bottom view thereof, the perforations shown in dashed lines being no part of the claimed design;

FIG. 4 is a right-side view thereof;

FIG. 5 is a left-side view thereof; and,

FIG. 6 is a perspective view thereof.
